UNITED STATES PATENT OFFICE

ROBERT E. MANLEY, OF YORK, PENNSYLVANIA, ASSIGNOR TO MANLEY MANUFACTURING COMPANY, OF YORK, PENNSYLVANIA, A CORPORATION OF DELAWARE

SERVICE RUNWAY

Application filed September 2, 1925. Serial No. 54,103.

This invention relates to service runways and has for its principal object the provision of a sturdy runway that can be built at a low cost which will offer minimum obstruction to passage of the workmen, and which will have a very high factor of safety in operation even with very heavy automobiles.

A further object of the present invention is to produce an efficient runway of wood and of standard steel sections and so assembled as to provide extreme rigidity.

In the drawings:—

Figure 1 is a perspective of the runway.

Figure 2 is a transverse section illustrating the principal truss.

Figure 3 is a side elevation of the step bracket.

Figure 4 is a perspective view of the entrance end.

Figure 5 is a plan view of a central portion.

Figure 6 is an enlarged side elevation of a portion of the runway, with parts in section and parts broken away.

Figure 7 is a section on line 7—7 of Figure 6.

Figure 8 is a similar sectional view of one of the tracks with parts in elevation and parts in section.

The service runway in general consists of two similar longitudinal track supporting frames braced together at their rear ends and at their centers and held against relative movement at their extreme front ends where

the tracks incline to and rest upon the ground.

The main tracks 10 are horizontal and are preferably of two inch pine while the sloping or inclined tracks 11 are preferably of oak altho obviously these tracks can be made of

any material desired. I use wood as I find it preferable, not only because of the coefficient of friction between the oak and the rubber of the tires, but also because of the possibility of fastening cleats on the wood at a very

much lower cost than I could fasten cleats to metal, for example.

The center truss consists of a transverse beam 15 of angle iron having one side flange flat on the ground and the other flange or angle being vertical. To the vertical flange

of the beam 15 are secured four uprights 16 arranged in pairs forming two columns, the two upright members of each pair or column having near their top a cross piece 17 preferably of angle bar and forming the front support for the horizontal track 10 which however, does not rest direct upon the angle 17 but does rest upon two slats 19 to which the inclined track 11 is fastened as by the bolts 20 which pass thru a transverse strap 21 and also thru the slats 19 having nuts 22 bearing against the bottom surface of the slats.

The rails 25 and 26 are each of angle iron and run parallel thruout their entire extent save at the extreme front where they diverge as at 27 to form a guiding mouth for each runway. The rails 26 are each riveted or bolted to an upright post 16 as for example at 29 and to the lateral flange of the post 16 I bolt a small angular section 30 which is secured as 31 to the forwardly extending inclined rail 26. Each pair of uprights 16 has an inclined brace or diagonal 32 bolted to the transverse angle bar 17, the two posts 16, and also at its lower end to the ground angle iron or base beam, bracing the entire structure and forming a truss.

The rear truss is of similar construction save that the uprights 35 extend above the rails 25, each pair being joined at the top by a cross bar 36 forming the top of the column and spaced above the rails 25 approximately the same distance as the rails are spaced above the track 10, so that the cross bars 36 form a safety buffer or stop. Since the sloping braces or diagonals 32, the cross bars 17 and the beam 15 are exactly the same in the center and rear trusses I have given them the same numerals.

Each of these trusses is joined to the upper rail 25 by means of a rather long sloping brace 40 secured to the adjacent upright 16 or 35, as the case may be, at the bottom and also bolted to the upper rail as at 41, the bolt 41 on each side forming the supporting member for a hanger 43 which is in the form of a U or a stirrup and which is bolted to the horizontal track 10 as at 50.

The front supporting frames located mid-

way of the inclined tracks 11 are each formed of a pair of vertical angle bars 52 joined at the bottom by rests 53 of angle iron and are bolted at their tops to the rails 26 as at 55. Each prop 52 supports the inclined track 11 by means of a small strap of angle iron 57 one flange of this angle piece lying flush against the bottom of the track and the other flange lying flush against the side of the prop or standard 52 to which it is secured by means of a bolt 58 but preferably this angle piece is not secured to the oak incline or track 11 which has its sole fastenings between its two ends to the two hangers 60 each of which is suspended from the rails 26 midway between the central support formed by the two standards 52, and the rests 53, and the adjacent end of the board or track.

The inclined track 11 is provided with cleats at proper intervals, a dozen or more in number, positioned so that the cleats shall not be directly over one of the hangers 60 or directly over the rest 53. These cleats 62 may be secured in place in any desired manner, as for example by means of screws or fastenings 65. The cleats not only aid in increasing the tractive effort in going up the incline but they, like the several hangers, prevent the wood of the tracks from splitting.

At the extreme front end the two front stirrups or hangers 66 are held together by a flat tie strip 67 to maintain the proper spaced relation between the two tracks. Preferably the flare in the front guard rails begins at the point of fastening of the front stirrups or hangers 66 and the rails.

I find it very convenient to provide a step which I locate about midway of the platform formed by the horizontal tracks. This step is formed of a board 70 supported by a bracket having a horizontal portion 71 to which the board 70 is secured, a vertical section 72, and an upper horizontal section 73 underlying the horizontal track 10 and secured to it in any desired manner. I find it very advantageous to use a small piece of a large non-symmetrical angle iron such as 75 and have the shorter leg or flange of the angle overlie the top of the track 10 while the other and longer flange overlies and is riveted to the upper portion of the vertical section 72 of the bracket.

In the drawings I have shown four compression members preferably rectangular posts 77 of yellow pine each located midway between the small central standard 78 and the adjacent truss. These wooden posts are not essential but are nevertheless extremely convenient and efficacious and relieve the steel work of the service runway of considerable stress when a heavy car is standing upon the horizontal portion, and add to the length of life of the runway.

What I claim is:—

1. In a service runway, a pair of trusses, a pair of tracks having their ends supported by said trusses, a guide rail for each track, a pair of diagonals each secured at its upper end to one of said guide rails and at its lower end to the adjacent truss and a stirrup supported by said rail and diagonal and supporting said track between the trusses.

2. In a service runway, a plurality of parallel tracks each consisting of two sections, one horizontal and the other inclined, a truss at the junction of the horizontal and inclined sections, said truss consisting of a base, four uprights rising from said base, diagonals each secured to said base and the adjacent uprights, a cross piece spaced below the top of the uprights and furnishing a support for the two sections of the track, a guide rail secured to the top of each of said uprights, means at the front end of the runway for holding the free ends of the inclined tracks spaced from one another and for holding the guide rails in spaced parallel position above said tracks, a truss at the rear end of the runway consisting of a base member, two pairs of uprights rising from the base member, said uprights supporting the rear end of the guide rails and rising above said guide rails, and a plurality of stirrups suspended from each pair of guide rails for supporting said tracks.

3. In a steel and wood service runway, a plurality of pairs of spaced angle iron guide rails, the rear half of said guide rails being horizontal and the front half being inclined downwardly to the ground or other supporting medium, the guide rails of each pair being outwardly flared at their ground or forward ends, means for supporting said guide rails in said positions and a plurality of hangers suspended from the guide rails at intervals and tracks secured to and supported by said hangers.

4. In a service runway, a pair of trusses each consisting of a rolled steel base member, a plurality of rolled steel uprights, rolled steel transverse members connecting adjacent uprights to form two columns, braces secured to the base member, the two adjacent uprights of each column and to the transverse member, guide rails secured to said trusses, a sloping brace extending from the bottom of each upright upwardly and inwardly to the guide rail, and means secured to each sloping brace and to the guide rail for centrally supporting a track held at each end by one of said transverse members.

5. In a service runway, a truss consisting of a base member, two columns each of two vertical angle irons, a cross piece spaced below the top of adjacent vertical angle irons, a track supported at its center by said truss, means for supporting said track at its rear and front ends, a guide rail secured to the top

of each vertical angle iron and secured at its free ends to the said means, and means secured to the base of said truss for supporting a portion of the track between said truss and

5 the adjacent track support.

In testimony whereof I affix my signature.

ROBERT E. MANLEY.
